(57) **CLAIM**

The ornamental design for a dumbbell with holes, substantially as shown and described.

DESCRIPTION

FIG. 1 is a perspective view, showing the dumbbell with holes;

FIG. 2 is a frontal view of the FIG. 1 dumbbell with holes, the top, bottom and rear views being the same;

FIG. 3 is a left end view of the FIG. 1 dumbbell with holes, the right end view being the same;

FIG. 4 is a frontal view of a modified embodiment of the dumbbell with holes, the top bottom and rear views being the same, and the end views being the same as FIG. 3; and, FIG. 5 is a perspective view of a second modified embodiment of the dumbbell with holes.
